DUPLICATING MACHINE

Alfred E. Goodwin, Ottumwa, Iowa

Application June 15, 1936, Serial No. 85,243

6 Claims. (Cl. 101—116)

The object of my invention is to provide a duplicating machine of simple, durable and inexpensive construction. More specifically, it is my object to provide a machine of this class in which the sheets of paper will be fed rapidly and accurately to the stencil and platen.

A further object is to provide an improved stop and guide device for the sheets of paper, to aid the operator in quickly and accurately feeding sheets of paper to the machine.

A further object is to provide improved and simplified means for detachably connecting the stencil holder with the rotatable shaft and for quickly and accurately aligning the stencil holder relative to the shaft.

In the accompanying drawing Figure 1 shows a top or plan view of my improved duplicating machine.

Figure 2 shows a vertical longitudinal sectional view of same.

Figure 3 shows a vertical transverse sectional view through the paper holding platform and illustrating the paper stop and guide device.

Figure 4 shows a perspective view of the stencil holder detached.

Figure 5 shows a detail sectional view illustrating the means for detachably centering the stencil holder relative to the end plates; and

Figure 6 shows an end elevation of the side paper platform.

Referring to the accompanying drawing I have used the reference numeral 19 to indicate generally the frame of the machine. This frame has at one end two upwardly extended arms 11, their upper ends being extended over the body portion of the frame, as shown by dotted lines in Figure 2, thereby forming a paper passageway from the side of the machine to the side of the frame under the arms 11. On the end of the frame opposite the arms 11 there is fixed a paper platform 12 extending the full width of the frame and to a point near the ends of the arms 11.

An auxiliary paper platform is provided and comprises a platform 13, made of sheet metal and having at its ends downwardly extended flanges 14 to engage the side of the paper platform 12. At the outer end there is an upwardly extended flange 15, and a rod 16 is hooked to this flange and pivotally mounted in the adjacent arm 11 so that this auxiliary paper platform may be readily and easily detached. The two platforms 12 and 13 constitute a paper platform.

The roller platen 17 is mounted in the ordinary manner on two arms 18 pivotally connected at 19 and extended upwardly, and each having its upper end connected to a spring 20 fixed to the frame for yieldingly holding the arms at their upper limit and holding the roller platen at its upper limit. The upward limit of the movement

of these arms 18 is controlled by a screw 21 engaging a lug 22 on the frame.

For moving the roller platen downwardly to an inoperative position I have provided a shaft 23 mounted to the frame and having a handle 24 at one end and an arm 25 to engage the upper edge of the arm 18. By moving the handle 24 upwardly from the position shown in Figure 2 the arm 25 is moved downwardly to lower the roller platen, and when the handle 24 is in the position shown in Figure 2 the spring 20 holds the roller platen yieldably at its upper limit.

Mounted in the arms 11 is a shaft 26 having a crank 27 at one end. Fixed to this shaft are two end plates 28, and these end plates are formed with tapered openings 29, as shown in Figure 5.

The ink pad and stencil holder shown in Figure 4 comprises two end members 30 and a cylindrical perforated body portion 31, and an ink pad and stencil 32 which is mounted upon the outer surface of the body portion 31 and yieldingly held in position thereon by a spring 33.

Seated in each of the end plates 30 is a screw 34 having a tapered body portion 35, the taper corresponding to the taper of the openings 29. These end plates 30 are formed with slots 36 designed to receive the shaft 26.

The entire ink pad and stencil holder is of cylindrical shape, but one side is cut off so that when in the position shown in Figure 2 the ink pad and stencil holder is widely spaced apart from the paper platform 12.

For the purpose of stopping and accurately guiding the sheets of paper I have provided a stop and guide plate 37 having at one edge an upwardly extended flange 38 and at another edge an upwardly extended flange 39. This stop and guide plate is provided with a slot extended transversely through it, as shown in Figure 2, and through this slot there is extended a flat rod 40 of resilient material. This rod 40 has a downwardly inclined end 41 to engage the side of the paper platform 12, and at its other end there is a downwardly extending portion 42 adjacent the opposite side of the paper platform. Mounted on this downwardly inclined end 42 is a screw 43, and mounted upon the rod 40 is a flexible pad 44 made of leather or the like. In operation, when this screw 43 is moved outwardly the rod 40 becomes substantially straight and the stop and guide plate may also be freely moved longitudinally of the paper platform. When, however, the screw 43 is moved inwardly, the outer end of the rod 40 is inclined upwardly, as shown in Figure 3, which forces the central portion of the rod 40 downwardly, bringing the plate 37 into frictional binding engagement with the paper platform above.

In practice I have found with my improved duplicating machine that I can attain greater

speed and do more accurate work than with the duplicators now in common use. In practice I place the blank sheets of paper upon the paper platform 13, and then I adjust the stop 5 and guide device to the proper position for the sheets selected and for the character of the stencil used. Then I may, with the left hand, grasp the sheets of paper and move them laterally and forwardly across the paper platform 12 10 along the dotted lines 45, as shown in Figure 1. This is possible because of the paper passageway formed in the adjacent side of the frame and because the stencil holder is in position widely spaced apart from the roller platen, and 15 when in this position the paper projects over the roller platen so that when the handle crank 27 is turned, the stencil will engage the paper and grip it against the roller platen and thereby complete the printing upon the paper in the 20 ordinary manner. However, by this arrangement only one movement in a substantially straight line of the paper is required to be done by the operator's left hand. Heretofore it has been necessary to feed the sheets of paper first 25 forwardly into the machine and then backwardly against the paper guide, and again forwardly into position over the platen, and this requires additional time. With my machine a single movement of the paper in a straight line 30 is all that is required, and when that is done, the paper is accurately guided and held in position relative to the platen.

With my improved paper stop and guide device I have demonstrated in use that when the 35 screw 43 is loosened, the plate 37 can be readily and easily moved both laterally and longitudinally to the desired position, and then when the screw 43 is tightened it is firmly clamped in that position.

40 I have further demonstrated in practice that with my improved machine I can rapidly and accurately reproduce printing in several colors, and I do this as follows: I provide several of the ink pads and stencil holders, place one color 45 of ink and the stencil in one holder and the remainder of the stenciled design on another ink pad and stencil holder to which another color of ink is applied. I then proceed in the ordinary manner of duplicating machines, to 50 print on the sheets of paper from the first stencil, and then remove the first stencil and substitute the second stencil with a different colored ink, and run the paper through the machine the second time. This obviates the necessity of re- 55 moving one ink pad and stencil holder and cleaning the stencil holder before applying the second stencil and ink pad with the different color, as is now the general practice.

I claim as my invention:

60 1. A duplicating machine, comprising a frame, a rotary ink pad and stencil carrier mounted in the frame, a roller platen mounted in the frame in position to hold paper against the stencil, a paper platform carried by the frame and extending 65 from the position where it will support sheets of paper on one side of the frame and during their movement from said position to feeding position, the frame being so shaped as to permit said movement of sheets of paper in a straight 70 line, and said ink pad and stencil holder being so shaped that in one position of its rotary movement it will be widely spaced above the roller to permit said movement of the sheets of paper.

2. A duplicating machine, comprising a frame, a roller platen carried by the frame, the side of the frame directly above the platen being formed with a passageway for sheets of paper, a rotary ink pad and stencil carrier mounted in the frame above the platen and being of segmental form whereby when in one position of its movement it will be widely spaced above the platen, and a platform for paper sheets extending from the position for supporting sheets of paper at the side of the frame adjacent said paper passageway to paper feeding position at the front of the machine.

3. A duplicating machine, comprising a frame, a roller platen carried by the frame, the side of the frame directly above the platen being formed with a passageway for sheets of paper, a rotary ink pad and stencil carrier mounted in the frame above the platen and being of segmental form whereby when in one position of its movement it will be widely spaced above the platen, and a platform for paper sheets extending from the position for supporting sheets of paper at the side of the frame adjacent said paper passageway to paper feeding position at the front of the machine, the portion of the paper platform at the side of the frame having its inner end resting upon the frame and a rod for supporting the outer end of said platform to the frame, said rod being detachably connected at one end.

4. In a duplicating machine, the combination of a rotatable cylinder containing an ink pad and a stencil, a stationary paper platform, a paper stop and guide device, comprising a flat plate having a stop and guide flange extended upwardly, and also having an opening extended through it transversely of the platform, a resilient rod slidably mounted on the platform and having one end inclined downwardly at one edge of the platform, and a means carried by said end of the rod for forcing it away from the edge of the platform and thereby bending the central portion of the rod downwardly to force the plate into binding frictional engagement with the platform.

5. In a duplicating machine, the combination of a rotatable cylinder containing an ink pad and a stencil, a stationary paper platform and a paper stop and guide device, comprising a flat plate having a stop and guide flange extended upwardly, and also having an opening extended through it transversely of the platform, a resilient rod slidably mounted on the platform and having one end inclined downwardly at one edge of the platform, and a means carried by said end of the rod for forcing it away from the edge of the platform and thereby bending the central portion of the rod downwardly to force the plate into binding frictional engagement with the platform, said latter means comprising a yielding pad carried by the rod and a screw seated in the downwardly inclined end of the rod for forcing the pad against the platform.

6. In a duplicating machine, the combination of a shaft, two supporting plates carried by the shaft and each having a tapered opening, a stencil holder detachably mounted between said plates, tapered set screws seated in the stencil holder and extending outwardly through said tapered openings and whereby upon tightening the screws the stencil holder will be accurately positioned within the supporting plates.
